UNITED STATES PATENT OFFICE.

BURLEIGH PUTNAM, OF PASADENA, CALIFORNIA.

MACHINE GUN.

Application filed August 30, 1917. Serial No. 188,921.

To all whom it may concern:

Be it known that I, BURLEIGH PUTNAM, a citizen of the United States, residing at Pasadena, in the county of Los Angeles, State of California, have invented a new and useful Improvement in Machine Guns, of which the following is a specification.

My invention relates to firearms which are arranged to fire consecutively when once started until they are either stopped by the gunner or until the supply of ammunition fails.

The principal object of my invention is to produce a gun which shall be positive in operation, which shall have few parts, and which shall be light in weight and inexpensive to construct.

These objects are accomplished by the use of a reciprocating barrel which is blown or pulled forward by the explosion of the cartridge and by the use of cartridges which are mounted in sets of ten or more in a clip in which they are fired and in which they are fed into the gun as a unit.

As the cartridge shells are ordinarily formed of light sheet brass they expand in the barrel during the time of the explosion due to the high pressure of the gases therein at that time and they therefore tend to grip the chamber of the barrel in which they are fired and thereby prevent the forward movement of the barrel. It is a further object of my invention to provide an oiling device which shall form a part of the gun and by means of which the shells shall be thoroughly lubricated just before they are fired.

I have found that while there is a strong tendency for the barrel to move forward as the cartridge is discharged that this force under some conditions and with some charges is insufficient to start the barrel especially where the shells are partly or insufficiently lubricated. It is a further object of my invention to provide an actuator which is operated by the gases of the explosion and which is so arranged that the barrel is moved forward with considerable force at the moment of the explosion.

In some types of guns it is sufficient to provide clips containing from ten to thirty shells and to provide for hand reloading of the gun after each clip is fired. In other types of gun it is desirable to provide for firing a much larger number of shells without reloading. It is a further object of my

invention to provide a magazine which shall hold a number of clips and to provide a mechanism by which these clips are automatically fed into the gun in order and fired 60 consecutively.

A further object of my invention is to provide a novel form of clip in which the standard United States Army ammunition may be loaded. This ammunition has the 65 head of the shell the same diameter as the body, the head being separated from the body and in reality formed by an extractor groove formed in the body of the shell and of somewhat smaller diameter at its base 70 than the diameter of the body.

A still further object of my invention is to provide a novel form of magazine in which a plurality of clips may be mounted and in which they can be readily loaded 75 and transported and in which they may be placed in such relation to the gun that they can be readily fed thereto.

I have found that it is desirable to load the magazines with fifty rounds which may 80 be made up of ten clips of five shells each or preferably of five clips of ten rounds each and such a magazine with its load will weigh about four pounds. To reduce the labor of handling I have devised a container which will take twelve magazines and which will weigh loaded about fifty pounds. This container I make in cylindrical form so that it is compact and may be 85 easily rolled about to save lifting. 90

As guns made according to my system are very compact and are very positive in their action due to the large forces available for their actuation they are inclined to shoot very fast, a model gun made without any 95 attempt to get high speed having fired over twelve hundred shots a minute. As a high speed is in most cases desirable in a machine gun this is not a disadvantage in the case of my invention but there are some cases in 100 which a lower speed is desired. A further object of my invention is to provide means by which the gun can be so constructed as to materially reduce its natural high speed. This I accomplish by what I call a retarder. 105

The United States Army demands and it seems desirable to build two types of machine guns known as the light type and the heavy type respectively. In the heavy type a water jacket may be used around the 110 barrel for the purpose of cooling it, but in the light type gun the weight of the jacket

and the water make such a scheme impractical and it is further objectional as it is often desirable to use machine guns in locations where water is a scarce article. For 5 the light gun it will be probably sufficient to provide the barrel with cooling ribs but I have devised certain novel systems of cooling which I have incorporated in the following specification. These systems are 10 possible in my invention on account of the fact that I have a moving barrel and on account of the fact that the barrel movement is considerable, being about four 15 inches.

15 Further objects and advantages will be made evident hereinafter or will be evident to one skilled in the machine gun art after an inspection of the accompanying drawings and a perusal of the following specification.

20

In the drawings which are somewhat dia-grammatic,

Fig. 1 is a side elevation of the muzzle end of a machine gun embodying my invention, a portion thereof being shown in section to better illustrate the novel features thereof.

Fig. 2 is a similar view of the breech end of the same gun the stock of which is shown broken away as stocks are old in the art and form no portion of the present invention. The gun shown in Figs. 1 and 2 is in the open or cocked position.

Fig. 3 is a plan view looking down on the 35 top of the gun, portions thereof being broken away or shown in section and portions beyond the immediate foreground being omitted for the purpose of making the spirit of the invention plain. In this view the 40 gun is shown in its cocked position with a magazine in place.

Fig. 4 is a section of the gun in its closed position on a broken plane indicated by the line 4—4 of Fig. 2, this plane being 45 viewed in the direction of the arrows.

Fig. 5 is a section of the gun in its closed position on a plane indicated by the line 5—5 of Fig. 4, this plane being viewed in the direction of the arrows.

50 Fig. 6 is a section on a plane indicated by the line 6—6 of Fig. 4 this plane being viewed in the direction of the arrows.

Fig. 7 is a sectional elevation of one of the feed dogs shown on an enlarged scale 55 from the previously described views.

Fig. 8 is a perspective view on an enlarged scale of a portion of one form of clip.

60 Fig. 9 is a section through the same clip with a standard Springfield cartridge in place therein.

Fig. 10 is a front view of a portion of the form of clip shown in Fig. 9.

65 Fig. 11 is a front view of a portion of an alternate form of clip.

Fig. 12 is a section on a plane indicated by the line 12—12 of Fig. 11.

Fig. 13 is a side elevation viewed from the gun side of a magazine carrier and magazine in place therein.

Fig. 14 is a perspective view of an empty magazine.

Fig. 15 is a plan view of a container broken away to show how the magazines fit therein and how the clips fit in the magazines.

Fig. 16 is a side elevation of the container shown in Fig. 15 similarly broken away.

Fig. 17 is a sectional side elevation of one form of air cooling device.

Fig. 18 is an end view of the parts shown in Fig. 17.

Fig. 19 is a section on a plane indicated by the line 19—19 of Fig. 17.

Fig. 20 is a sectional side elevation of an alternate form of air cooling device.

Fig. 21 is a section on a plane indicated by the line 21—21 of Fig. 20.

Fig. 22 is an end view of the parts shown in Fig. 20.

In the form of my invention shown in the drawings a main frame 31 is provided with any desired form of well known stock not shown which may be attached to the frame 31 at 32. Mounted in a back guide 33 and a front guide 34 is a barrel 35 which is free to move forward from its firing position in which it abuts against a solid breech block 36 which forms an integral part of the frame 31. Threaded or otherwise secured in the front support or forward guide 34 is a bearing member 37 in which the barrel slides. Threaded or otherwise secured to the muzzle end of the barrel 35 is an actuator piston 38 which fits closely into an actuator cylinder 39 formed in the front end of the bearing 37. Formed on the barrel 35 are a series of cooling ribs 40 the front one 41 of which is somewhat elongated and forms a retarding piston which 105 fits closely in a retarding cylinder 42 formed in the rear end of the bearing 37. A small port 43 formed in the barrel 35 just back of the actuator piston, 38 serves as a gas vent to pass the gases of the explosion into 110 the gas cylinder 39 back of the actuator piston 38 when the gun is in the firing position so that these gases in expanding can force the barrel 35 forward from the firing position. A small vent port 44 formed in 115 the bearing 37 serves to permit the air compressed by the retarding piston 41 in the retarding cylinder 42 to escape as the piston 41 is driven home and also serves to allow air to enter the cylinder 42 as the barrel 120 is forced back thus relieving the partial vacuum formed therein by the recession of the piston 41.

Threaded or otherwise secured to the barrel 35 is a nut 50 which is such a shape 125

and size that it fits closely into an open sided box formed at the rear of the main frame 31 by a top 51, a back 52, and a bottom 53, all of which are preferably made 5 chined to fit closely about the nut 50. Secured to the nut 50 is an operating handle 54 which projects out to one side of the gun in a convenient position to be grasped by the gunner for the purpose of manually 10 actuating the barrel 35.

Secured in the back guide 33 and the front guide 34 is a spring tube 55 which contains an operating spring 56. This spring is of the compression type and presses at one end 15 on the closed front of the tube 55 and at its other end on the front of the nut 50. In actual practice the spring 56 is quite strong and tends to throw the nut 50 and the barrel 35 backward towards the breech 20 block 36 in the direction of the arrow 57 shown in Fig. 1. For the purpose of holding the gun in its open or cocked position a sear 58 is provided as shown in Fig. 2. The sear 58 is pivoted on a pin 59 and is 25 made integral with a trigger 60, being held in its engaged position by a light compression spring 61. A trigger guard 63 is provided which may conveniently connect to a pistol grip 64 formed or secured to the 30 bottom 53 of the frame 31.

For the purpose of retaining the nut 50 in the box formed by the parts 51, 52, and 53, a guide 65 may be used this guide being of a T section and projecting through 35 an open slot in the top 51 down into a slot formed in the top of the nut 50.

The standard form of cartridge now used by the United States Army and known as the Springfield has a head about the same 40 diameter as the body as shown in Fig. 9. One form of clip suited to hold such cartridges is shown in Fig. 8 and consists of a sheet of metal bent into a channel section having a web 70, and two flanges 71. Cut 45 in the web 70 are a plurality of open slots 72 which have a width corresponding to the diameter of the bottom of the extraction groove 73 of the standard shell 74. One flange 71 of the clip 75 is also cut away 50 to allow the head of the shell 74 to pass. In practice the shells 74 are forced into the slots 72 by an automatic loading machine which forms no part of the present invention and is therefore not illustrated. The 55 clips are made of material of about the same thickness as the width of the extraction groove 73 and if properly loaded the cartridges are firmly anchored in the clips so that they will not be jarred out in shipment. It is not necessary for the successful 60 operation of the gun that the shells be accurately placed as the bullets are tapered to a fine point and the barrel will cause the bullet to enter even if the shell be some- 65 what out of line and once entered the barrel

has enough force to rectify any moderate amount of displacement of the shell and indeed to reform shells that have been bent considerably out of round.

Other forms of clip may be used. For 70 example in Fig. 10 I show a modified form of clip in which small spring ears 77 are punched out of the material from which the clip is formed so that the clip is securely held in place about the shell 74.

In Figs. 11 and 12 I show still another form of clip in which a hole is first punched in the clip of the proper size to fit around the shell at the bottom of the extractor groove 73 and small radial cuts are then 80 made extending out from the hole which is sprung out so that the body of the shell may be forced therethrough. The clip is then reformed to force the tongues formed by the slits down about the cartridge at the 85 bottom of the extraction groove.

Cut in the face of the breech block 36 are a pair of clip grooves 80 of suitable size and shape to receive a clip 75 which is held therein by a clip retainer. Dovetailed in the block 36 is a feed bar 82 which has three feed dogs placed as shown in Fig. 5 which project from its upper surface and are constructed as shown in Fig. 7. They consist of small bars of hardened steel having an inclined upper face 84 and an engaging face 85. A spring 86 forces them upwardly into notches 87 cut in the edge of the clips 75.

The feed bar 82 is reciprocated across the 100 face of the breech block 36 by means of a cam lever 90. This lever is pivoted on a pin 91 secured in the bottom 53 of the frame 31 as best shown in Fig. 4. One end is provided with a slot 92 which engages a pin 105 93 carried in an opening in the feed bar 82, the other end being curved and engaged by a slot formed in the bottom of the nut 50. The parts are so proportioned that the barrel in moving forward from the firing 110 position as shown in Fig. 4 and Fig. 5 holds the cam lever in the position shown in those figures until the barrel is entirely out of the path of the cartridges. A further movement of the barrel forward then 115 feeds the feed bar 82 across the breech 36 in the direction of the arrows 95 of Fig. 4 and Fig. 5. During the early part of the backward movement of the barrel the feed bar moves in the opposite direction. When 120 the feed bar moves in the direction of the arrows 95 the clip 75 is fed into the gun a distance equal to the distance between two cartridges and on the return movement the clip remains stationary the dogs 83 slipping 125 down under the lip due to their inclined surface 84.

To prevent the overtravel of the clip 75 as it is advanced by the feed bar 82 and to prevent it travelling backward with the feed 130.

bar on the return stroke of the bar I provide a clip stop 100. This is in the form of a flat plate located in a slot 102 in the breech block 36 and pivoted on a pin 103. The 5 lower end 104 of the stop 100 projects slightly from the breech block near the bottom thereof, as shown in Fig. 2, so that it can be pressed in manually when it is desired to advance a clip with the gun wide open. A 10 small compression spring 105 holds the stop 100 in its engaging position in which the upper end 106 projects into the path of the clip 75 engaging the slots 87. The upper edge of the feed bar 82 is cut away to form 15 a cam surface 107 as shown in Fig. 4 into which the upper end 106 of the stop 100 also projects. As the gun starts to close from the position shown in Fig. 4 the feed motion of the feed bar 82 first moves the clip 75 sufficiently to throw the slot 87 away from, in front of the end 106 the end 106 being held out of engagement with the slot 87 by the edge of the feed bar 82. As soon as the feed bar has moved the clip 75 a short distance 20 25 the end 106 is released by the cam surface 107 but cannot move therein due to the fact that it rests against the edge of the lower flange 71 of the clip and slides thereon. As soon, however, as the next slot 87 comes along 30 the end 106 springs into it and arrests and stops any further movement of the clip forward and also prevents any backward movement of the clip on the return stroke of the feed bar 82.

35 For the purpose of exploding the shells a firing pin 110 is provided which moves in an opening cut in the breech block 36 and which is held in its open position by a small compression spring 111. The firing pin 110 40 is forced into the primer of the cartridge to be fired by a firing pin lever 112 pivoted in an open slot in the breech on a pin 113. The lever 112 is engaged at its upper end by a firing rod 114 which is held at its forward 45 end in a guide 115 in which it slides freely. The rod 114 is held in its forward position by a compression spring 116. The rod 114 is made of the proper length to be struck by the nut 50 just before the barrel 35 is fully seated on the shell 74 which is to be fired.

Under some conditions it is desirable to oil 50 the cartridges so that they can be easily extracted even when under pressure and for this purpose I provide an oiling device 120 55 which consists of a tube 121 secured to the nut 50 and moving with that nut and consequently with the barrel. A felt cylinder 122 is placed inside the tube 121 and is kept soaked with oil being filled with oil whenever 60 the gun is oiled. The tube 121 is so spaced with relation to the barrel that it is concentric with one shell when the shell ahead is in the barrel.

If the gun is allowed to fire all the shells 65 in any clip it will fire the last one and then

close outside the clip and must then be opened by hand before another clip can be inserted or fed from the magazine. This makes a delay in the operation of the gun and to prevent this delay we provide a magazine sear 130 which is so arranged that the gun is caught in the open position before the last shell is fired leaving it cocked with a loaded shell ready to fire. 70

The sear 130 is pivoted on a pin 131 secured in the side 52 of the frame 31 and is provided with a latching notch so placed that it can catch the lower edge of an opening 133 formed in the nut 50 as shown in Fig. 6. A spring 134 throws the sear 130 80 into its engaging position and it is held out of its engaging position when there is a clip projecting over its rear end which in that case will rest against the clip. The feed bar 82 is cut away as shown in Fig. 4 at 135 to 85 allow the sear to project under and be held down by the clip 75. As soon as the clip 75 feeds off from the above the rear end of the sear 130 the front end catches the nut 50 stopping the gun in a cocked position with 90 a loaded shell ready to fire.

The magazine shown in Figs. 11 and 12 allow a considerable number of shots to be fired without reloading. This magazine consists of a sheet metal box 140 having a 95 tight metal cover 141. The magazine is of sector form as shown. The clips are held in place therein by guide bars 142 and 143. The edges of the box are cut away as shown at 144 to provide feeding openings and finger grips are provided so that the magazines can be readily lifted out of a round container 150 in which they may readily be shipped. 100

Turning on a pin 162 secured to the outside of the side 52 of the frame 31 of the gun is a magazine carrier 160 which is rotated by a stiff spring 163 in the direction of the arrow 161. A magazine retainer 164 is also provided to hold the magazines in the 110 magazine carrier.

The gun shown in Figs. 1 and 2 is provided with cooling ribs on the barrel and for a light gun that is not to be fired too often such a method of cooling is entirely 115 adequate. When a gun is desired that will be called on to be fired more often some better means of cooling is desirable.

In Figs. 17, 18, and 19 one such method is shown. In this method cooling ribs are 120 provided which extend longitudinally of the barrel 35 as shown at 200. The barrel 35 with its ribs 200 slides freely in stationary tubes 201 which are fixed to the frame 31 of the gun and which are connected to a 125 larger tube 202 by connecting washers in air tight relationship. A piston 205 is formed integral with the barrel 35 and fits tightly in the tube 202 sliding freely therein as the barrel is reciprocated. As the cubical con- 130

- tents of the large tube displaced by the movements of the piston 205 is very much greater than the air space around the barrel between the ribs 200 there results a very rapid and efficient movement of air around these ribs as the barrel moves. The air is drawn in at the outer ends of the tubes 201 and expelled therefrom so that the barrel is quite efficiently cooled.
- 10 Another method of cooling the barrel is shown in Figs. 20, 21, and 22. In this method the barrel 35 provided with cooling ribs 200 is reciprocated inside a stationary tube 301 fixed to the frame 31 of the gun.
- 15 The tube 301 is flared out at the muzzle of the gun to form a cylinder 303 in which a piston 304 is free to slide. The piston 304 is frusto conical in shape and the cylinder 303 is about one half as long as the stroke 20 of the barrel 35. As the barrel moves forward it pulls fresh air into the spaces around the ribs 200 and on its return stroke it also forces fresh air obtained by the piston 304 passing out of the cylinder 303 into the spaces between the ribs 200. Other modifications of my cooling system are evident as for example those in which the barrel would be stationary and the enclosing tubes would reciprocate.
- 25 The method of operation of my invention is as follows: The gun is first cocked by grasping the handle 54 and forcing the barrel 35 to its extreme forward position where the nut 50 is caught by the sear 58.
- 30 A clip can then be inserted in the clip grooves 80 passing in until the stop 100 catches in the first of the slots 87 of the clip 75. The gun is now fired by pulling the trigger 60 which is held down so that as the barrel is forced forward due to the expansion 40 of gas in the actuator cylinder 39 the sear of gas in the actuator cylinder 39 the sear does not catch. The barrel is therefore immediately returned by the spring 56. During the latter part of the forward movement 45 however the clip has been fed forward one cartridge by the dogs 83 of the feed bar 82. the barrel in coming back therefore finds a fresh loaded shell ready for it and the operation is repeated until the clip pulls 50 off from above the end of the sear 130 which then catches and holds the nut 50 in its forward position. If a magazine is being used as soon as the clip pulls off from over the sear 130 it will also pull out from the 55 magazine so that the magazine will rotate under the force of the spring 163 to throw the next clip down against the top of the sear 130 thus releasing the barrel for more firing. As soon as this firing starts 60 the feed bar 82 will reach into the opening 144 of the magazine 140 and start the next clip into the gun. In practice there is a slight stop in the firing while the magazine is shifting but it is hardly noticeable. The
- gun equipped with a magazine will continue to fire until every shell in the magazine is fired except the last one. The empty magazine is then withdrawn and a full one inserted. As soon as the full magazine swings down on top of the sear 130 the gun can start shooting again.
- 65 My invention comprises the following new and useful conceptions.
- First, in a gun having a barrel that moves forward from the firing position as it is fired, an oiling device that lubricates the shell so that the gripping action due to the explosion of the shell is reduced to a minimum.
- 70 Second, in a gun having a barrel which moves forward from the firing position an actuator which so moves the barrel.
- Third, a magazine in which a number of short clips may be stored and from which they are withdrawn in order.
- 75 Fourth, special forms of clips for the Springfield ammunition.
- Fifth, the cylindrical container and the method of packing the special magazines therein.
- 80 Sixth, the retarder for slowing down the barrel.
- Seventh, the new forms of air cooling devices.
- 85 I claim as my invention—
1. In a gun, the combination of: a moving barrel; means for inserting cartridges in said barrel; and an oiling device actuated by said barrel lubricating the exterior of said cartridges before they are placed in 100 said barrel.
  2. In a gun, the combination of: a barrel member; a breech member, said breech member being fixed and said barrel member being movable with relation thereto; and means 105 carried on one of said members for lubricating a cartridge stationary with relation to the other member.
  3. In a gun, the combination of: a barrel member; a breech member, said breech member being fixed and said barrel member being movable with relation thereto; and an oiling device fixed to said barrel in such a position as to lubricate the exterior of the cartridges used in said gun before said cartridges are placed in said barrel.
  4. In a gun, the combination of: a barrel member; a breech member, said breech member being fixed and said barrel member being movable with relation thereto; and an oiling receiver fixed to said barrel, in which the cartridges are inserted before being inserted in the barrel.
- 110 In testimony whereof, I have hereunto set my hand at Springfield, Massachusetts, this 125 29th day of August, 1917.

BURLEIGH PUTNAM.
